DESIGN FOR A COMBINED BOTTLE AND EYE CUP

Sylvain Rosengart-Famel, Paris, France,

Application June 20, 1933, Serial No. 48,472

Term of patent 7 years

To all whom it may concern:

Be it known that I, Sylvain Rosengart-Famel, a citizen of the Republic of France, residing at Paris, France, 179, Avenue Victor-Hugo have invented a new, original, and ornamental Design for a Combined Bottle and Eye Cup, of which the following is a specification, reference being had to the accompanying drawing, forming part thereof.

In the drawing, Fig. 1 is a perspective view of

a combined bottle and eye cup showing my new design;

Fig. 2 is a central longitudinal sectional view through the bottle and eye cup; and

Fig. 3 is a transverse sectional view taken on the line 3—3 of Fig. 2.

I claim:—

The ornamental design for combined bottle and eye cup as shown.

SYLVAIN ROSENGART-FAMEL.
